UNITED STATES PATENT OFFICE.

PALLIE E. HORTON, OF COVINGTON, KENTUCKY.

CARD HOLDER.

Application filed October 17, 1925. Serial No. 63,136.

The device forming the subject matter of this application is a card holder, and the invention aims to provide an article of the sort mentioned which will be simple in construction and easily manipulated to hold and release a card, and to sustain the card on a support.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a device constructed in accordance with the invention; Figure 2 is a section on the line 2—2 of Figure 1; Figure 3 is a section on the line 3—3 of Figure 1.

The device forming the subject matter of this application comprises a resilient strip 1, made of metal, and provided at one end with a flattened foot 2. The strip 1 is supplied at its opposite end with a notch 3 forming pointed holding prongs 4 which are rearwardly extended. The strip 1 is supplied, at its last-specified end, with a tongue 5 located between the prongs 4 and spaced therefrom, the tongue projecting from the base of the notch 3. The tongue 5 is formed into a forwardly presented eye 6. In order to enhance its resiliency, and to provide room behind the strip 1, the

strip is outwardly bowed, as at 7, between the foot 2 and the prongs 4. A handle 8, generally in the form of a ring, is mounted pivotally in the eye 6. Any means 9, such as screws, may be used for attaching the strip 1 to a support 10, the screws or other fastening means passing through the foot 2. When the device is mounted on the support 10, the prongs 4 project backwardly against the support, as shown in Figure 2. The free end of the strip 1 may be pulled outwardly by means of the handle 8, and a card or other object may be inserted between the free end of the strip and the support 10. When the handle 8 is released, the prongs 4 will retain the card in place on the support 10.

It will be understood that the prongs 4 may be of any desired length, as occasion may demand.

What is claimed is:—

A card holder embodying a resilient strip provided at one end with a flattened foot, and provided at its opposite end with a notch which forms pointed holding prongs at the outer longitudinal edges of the strip, the last-mentioned end of the strip having a tongue that is located between the prongs, the tongue being fashioned into a forwardly extended eye located at the base of the notch, a handle pivotally mounted in the eye, and means for securing the foot to a support, the prongs extending rearwardly to engage and hold a card against the support, the prongs engaging the support, when the card is removed, thereby to space the handle from the support and to permit the handle to be grasped readily.

In testimony that I claim the foregoing as my own, I have hereto affixed my signature.

PALLIE E. HORTON.
